UNITED STATES PATENT OFFICE.

LYMAN H. COBB, OF FITCHBURG, MASSACHUSETTS, ASSIGNOR TO MARY ELIZABETH JOHNSON,
TRUSTEE, OF FITCHBURG, MASSACHUSETTS.

SAFETY-RAZOR.

No. 903,957.

Specification of Letters Patent. Patented Nov. 17, 1908.

Application filed September 29, 1906. Serial No. 336,799.

To all whom it may concern:

Be it known that I, LYMAN H. COBB, a citizen of the United States, residing in Fitchburg, in the county of Worcester and Commonwealth of Massachusetts, have invented a new and useful Improvement in Safety-Razors, of which the following is a specification, accompanied by drawings forming a part of the same, in which—

Figures 1 and 2 represent side and rear views respectively of the safety razor embodying my invention. Fig. 3 represents the under side of the razor head, the handle having been removed. Fig. 4 is a front view 15 of the head of the razor, and Fig. 5 is a detached view of the clamping cam by which the clamping plates are drawn together for holding the cutting blade in position, and Fig. 6 is a central sectional view of the head 20 of the razor and one end of the handle.

Similar reference letters and figures refer to similar parts in the different views.

My present invention refers to that class of safety razors comprising a head for holding a cutting blade, and mounted on the end 25 of a handle, said head consisting of a pair of clamping plates between which the cutting blade is held in position.

My present invention has for its object to 30 provide an improved means whereby the cutting blade may be securely clamped into position or released at will by a single operation, and it consists of introducing into the head of the razor a clamping cam provided with 35 a lever handle which, by a partial revolution, serves to crowd the clamping plates firmly against the cutting blade held between them.

Referring to the accompanying drawings, 40 1 denotes the handle and 2 the head of the safety razor embodying my invention. The head consists of a clamping plate 3 bent at right angles at 4 and 5 and returned upon itself forming a flange 6, and the plate 7 attached by a screw 8 to the end of the handle. Between the plates 3 and 7 is clamped a cutting blade 9. The blade 9 is inserted between the plates 3 and 7, and the plates are drawn together by means of a rotating cam 10 turning 45 freely on the end of the handle, and inserted between the clamping plate 7 and the flange 6. The flange 6 is capable of a sliding movement on the handle, and is provided with a raised rib 11, forming a cam surface 50 coöperating with a corresponding cam sur-

face 12 on the under side of the cam 10. The cam 10 is provided with a lever handle 13, having a depending lug 14, which enables the cam to be rotated by the pressure of the thumb or finger against the lug. When the raised rib 11 on the flange 6 is brought to 60 correspond with the recessed cam surface 12 on the cam 10 the cutting blade 9 will be released, and by turning the cam into position shown in Figs. 3 and 4 the opposing cam surface crowds the flange 6 downward and draws its connected clamping blade 3 firmly 65 against the upper surface of the cutting blade 9. In its clamped position the lever 13 and lug 14 are pushed back against the rear side of the head entirely out of the way 70 of the cutting edge of the blade 9, and not interfering with the free use of the razor.

I claim,

1. In a safety razor, the combination with 75 a handle and a clamping plate attached to the end of said handle, of a second clamping plate and a clamping cam arranged to lock said plates in contact with a razor blade between them.

2. In a safety razor, the combination with 80 a handle and a clamping plate attached to one end of said handle, of a second movable clamping plate bent around one edge of said attached clamping plate, and having a flange 85 parallel to said movable clamping plate, and a cam interposed between said flange and said attached clamping plate for drawing said clamping plates together.

3. In a safety razor, the combination of a 90 handle, a clamping plate attached to the end of said handle, a movable clamping plate on one side of said attached clamping plate and having a flange integral therewith and extending across the opposite side of said attached clamping plate, a cam surface on 95 said flange, and a cam rotatable about the handle and coöperating with said cam surface.

4. In a safety razor, the combination of a 100 handle, a clamping plate attached to said handle, a movable parallel clamping plate, and a cam rotatable about the axis of the handle, whereby said clamping plates are drawn together.

5. In a safety razor, the combination of a 105 handle, a clamping plate attached to said handle, a movable clamping plate parallel with one side of said attached clamping plate, a cam rotatable around said handle on 110

the opposite side of said attached clamping plate, and a flange connected with said movable clamping plate and provided with a cam surface cooperating with said rotatable

5 cam.

6. In a safety razor, the combination with a handle, a clamping plate attached to said handle, a movable clamping plate on one side of said attached clamping plate, a cam 10 rotatable about said handle on the opposite

side of said attached clamping plate, and operatively connected with said movable clamping plate.

Dated this nineteenth day of September 1906.

LYMAN H. COBB.
